UNITED STATES PATENT OFFICE.

JOHN L. WEVER, OF MARION, INDIANA.

DESIGN FOR A PITCHER, &c.

SPECIFICATION forming part of Design No. 23,578, dated August 21, 1894.

Application filed July 21, 1894. Serial No. 518,278. Term of patent 14 years.

To all whom it may concern:

Be it known that I, JOHN L. WEVER, a citizen of the United States, residing at Marion, in the county of Grant and State of Indiana, 5 have invented and produced a new and original Design for a Pitcher or Similar Article; and I do hereby declare the following to be a full, clear, and exact description of the same, reference being had to the accompanying drawings, forming a part thereof.

Figure 1, is a front view of the pitcher, or similar article. Fig. 2, is a side view of the same.

The leading features of my design consist 15 in a man sitting straddle a barrel or cask. The

man having in one hand a bottle and in the other a glass. The stopper forming part of his hat. The barrel is provided with a faucet and a handle is attached to the back of the man.

What I claim is—

The design for a pitcher or similar article, as herein described and shown.

In testimony whereof I affix my signature in presence of two witnesses.

JOHN L. WEVER.
